BRASSIÈRE

Greta Katz, Beverly Hills, Calif.

Application March 21, 1949, Serial No. 82,620

2 Claims. (Cl. 2—42)

1

Summarizing, this invention relates to a brassière construction, and particularly to a construction in which a band is attached to the cups of the brassière, adjacent the separation between the cups, which band is substantially independent of the brassière at the cups, and embraces the body and holds the separation against the chest.

It is particularly adapted for use in deep V-neck or notched brassières, as, for example, those worn with dresses with plunging necklines. I employ a V or U-shaped wire to form the notch V-neck and connect the band to the legs of the V or U, and provide a band which, independently of the brassière, straps the notch against the chest.

The object of my invention is to assure that the portion of the brassière between the cups lies flat against the chest when the brassière is worn. The sides of the V or U frame thus form an uplifting support for the edge of the breast at the chest and prevent the breasts from falling together or drooping to form the ugly line produced when the breasts come together at the separation.

In most brassières, the tension is over the shoulders and across the back, produced by the tightening of the shoulder straps and making the brassière snug. Due to the protuberance of the breasts, the line of tension across the breasts and around the back, if sufficient to hold the portion of the brassière over the separation flat, results in a flattening of the breasts.

Since it is the purpose of the cups of the brassière to uplift and hold the breasts in a youthful moulded fashion, the tightening of the band and shoulder straps sufficient to hold the separation flat against the chest is undesirable. However, if the tension is not so sufficient, the weight of the breasts, especially in full-bosomed women, is sufficient to cause the cups to sag and to cause the brassière at the separation to fall outward, permitting the breasts to approach and touch.

This is especially aggravated in deep V-necked or notched brassières to be worn with dresses designed with décolletage or plunging necklines.

By separating the support for that portion of the brassière which overlies the sternum (separation between the breasts), i. e. from the cups, I

2

may at the same time support the brassière portion lying between the breasts firmly against the chest without causing any undue pressure of the cups against the breasts.

I accomplish this by employing a band which may embrace the body, pass under the breast, and connect to the brassière at the separation. The brassière proper is independent of the band at least in that portion thereof which overlies the breasts, so that the tension of the band may be as much as is necessary to hold the brassière at the separation flat against the chest without causing an equivalent tension in the fabric of the brassière over the breasts.

These and other objects of my invention will be further described in the following, taken together with the drawings, in which

Fig. 1 is a perspective front view of one form of the brassière in wearing position;

Fig. 2 is a back view of the brassière partly in section;

Fig. 3 is a back plan view of the brassière; Fig. 4 is a section taken on line 4—4 of Fig. 3; Fig. 5 is a fragmentary section taken on line 5—5 of Fig. 1;

Fig. 6 is a top view of the brassière in closed position;

Fig. 7 is a back plan view of one modification of the brassière; and

Fig. 8 is a top view of the brassière of Fig. 7.

The brassière is formed of two cups 1 having a notch 2 at the separation of the breasts framed by a U or V-shaped relatively stiff wire 3 encased in a fabric sheathing 4. The base 6 is at the bottom of the notch and legs 5 of the wire frame 3 of the notch 2 extend upward close to the top edge of the brassière. The cups are formed in the conventional manner and when worn the wires are positioned at or near the base of the cups and the top ends of the legs 5 are in line with the points 7, the wire being positioned in the separation between said cups and along the contiguous sides of said cups.

The wire frame is mounted in and the cups are joined at stitch lines to the front panel 10. The side panels 11 having gussets 12 are connected to the rear panels 13 which carry hooks and eyes 14 and 15.

The shoulder straps 9 are connected as conventional to the upper points 8 in line with the

cup points 1. The construction thus far described is for a deep brassière. For short brassières the panels 10, 11, and 13 are made much shorter, and panel 10 may, in fact, be nothing but a band connecting panels 11 and the cups. This will be readily understood by those skilled in the art.

The independent band is composed of two parts 16 and 16a connected to the fabric at stitch line 17. The ends of the band and stitch line extend upwardly of the legs 5 so that they are connected to the fabric not only adjacent the base 6 but also along the legs 5. The purpose of this method of construction is to strap the sides of the notch against the chest and prevent the wire frame 3 from rotating on its base or otherwise falling outward under the weight of the breasts in the cups.

It will be observed that this is accomplished because the band at the point of juncture 17 along the separation between the contiguous edges of the cups (i. e., along legs 5) is in tension to cause the separation to be flat against the chest. This tension need not be large but should be sufficient when added to the action of the cups to prevent the breasts from falling toward each other.

The band need not be connected to the base 6 but preferably should extend along the legs 5 sufficiently to insure that the separation along its whole length lies flat against the chest. Thus, it will not be necessary, although it may be permissible, to extend the component parts 16 and 16a of the band to embrace the base 6 provided the ends extend also along the legs 5, as described above.

In the form shown in Figs. 1, 4, and 6, inclusive, the band is entirely independent of the brassière except where it is joined thereto adjacent the legs 5. The ends of 16 and 16a are hooked or otherwise fastened at the back independently of the brassière proper.

In the form shown in Figs. 7 and 8 the band is independent of the brassière except where it is joined to the notch and legs 5 at the separation and at the back panels 13. In this construction the length of the brassière is preferably fuller than the bands 16 and 16a, that is, the longitudinal dimension of the brassière between the stitch line 17 at the notch and the stitch line 17' or other juncture of the band to the back panels is greater than the unstretched length of the bands 16 and 16a between their ends.

In both forms of the brassière the bands 16 and 16a are cut to form a concave edge 18 at that portion of the upper edges of the bands which lies adjacent the cups. The concaved edges are covered with some soft material 19.

The above construction of the brassière results in the following position of the brassière parts on the body. The brassière is put on in the conventional manner by slipping the arms through the shoulder straps 9. The bands 16 and 16a are placed about the body with the concaved edge 18 against the body and underneath the breasts and the bands are joined at the back of the body. These bands thus strap the notch of the brassière and the frame work snugly and firmly against the chest at the separation of the breasts. It will be observed that the band tension is exerted not only at the base but on the legs so that not only is the base strapped to the chest but also the side legs. I believe this to be important since, as will be observed, if only the base of the separation is strapped to the body, the top of the frame will fall forward, and if this results the

breasts will be permitted to fall out of the cups. Also the contoured edge 18 and the snug fit of the bands about the body have a contour-forming action to assist the cups in providing the desirable uplift of the breasts. The brassière is then joined at the back by means of the fasteners 14 and 15. Since the cups of the brassière and bands are independent, the tension of the bands is not communicated to the fabric of the brassière at the cups, and therefore the cups merely act as pockets for the breasts with the nipples of the breasts at the points, conforming the breasts to the shape of the pockets. It will be observed that the fabric of the cups is not tensioned by the bands. The bands do, however, strap the wire frame and notch against the chest. It will also be observed that the position of the legs 5 against the chest prevents the breasts from falling out of the cups toward each other and therefore the breasts cannot meet at the separation.

A similar result is obtained from the form shown in Fig. 7. The single difference lies in the fact that the ends 16' of the bands 16 and 16a are joined to the back panels so that one fastener will fasten the ends of the brassière and of the bands. It will be noted, however, that to prevent the brassière from producing a circumferential hoop tension at a line crossing the cups, by reason of the hoop tension in the bands 16 and 16a when the brassière is worn, sufficient fullness should be provided in the brassière so that the cups are of the desired conformation, when the brassière is worn, to mould but not flatten the breasts.

It will also be recognized by those skilled in this art that if a notch is not desired, it may be covered with cloth, as by extending the panel 10 over the notch. Additionally, the frame need not be U or V-shaped, but may be a plate or even a single wire, or may, in fact, be omitted. The bands may be connected to the brassière at the separation both at the base of the cups and part way up the separation. In this manner the portion of the brassière between the cups may be independently strapped against the chest to hold that portion flat without imparting hoop tension to the fabric of the brassière proper.

While I have shown the bands as joined in the back, which, I believe, is most desirable, the bands may be joined at any other portion, provided means are employed to pass the bands around the body and join both ends to the brassière at the separation as indicated.

While I have described a particular embodiment of my invention for the purpose of illustration, it should be understood that various modifications and adaptations thereof may be made within the spirit of the invention as set forth in the appended claims.

I claim:

1. A brassière comprising a pair of spaced cups, each cup including a base and a point, said cups having opposing contiguous reinforced edges spaced from each other, a band, one end of said band connected to each of the opposing contiguous edges of said cups between the base of the cup and the point, the upper edge of said band adjacent the base of said cups being positioned beneath the base of said cup, said band being otherwise disconnected from said brassière at said cups, the edge of said band adjacent said cup being concave to fit under the breasts when the brassière is worn, and means for securing said band and the brassière about the wearer.

2. A brassière comprising a pair of spaced cups, each cup having a base and a point, wire reinforcement secured to the contiguous edges of said cups, the brassière being cut away between said contiguous edges at the separation between the cups to form a notch between said contiguous edges, a band, one end of the band being connected along said reinforced edges between said base and the points of said cups, the upper edge of said band adjacent the base of said cups being positioned beneath the base of said cups and contoured to fit under the breasts when the brassière is worn, said band being disconnected from said brassière adjacent the base of said cups.
